[57] CLAIM

The ornamental design for a cover of a carrier for a vehicle, as shown and described.

DESCRIPTION

FIG. 1 is a perspective view of the cover of a carrier for a vehicle showing the new design;

FIG. 2 is another perspective view thereof from a different viewing position than shown in FIG. 1;

FIG. 3 is an elevational view of one end thereof;

FIG. 4 is an elevational view of the opposite end thereof;

FIG. 5 is an elevational view of one side thereof;

FIG. 6 is an elevational view of the opposite side thereof;

FIG. 7 is a top plan view thereof; and,

FIG. 8 is a bottom plan view thereof.

The broken lines shown in FIGS. 1-6 are for illustrative purposes only and form no part of the claimed design.
